UNITED STATES PATENT OFFICE.

BYRON B. BOWER, OF BAINBRIDGE, GEORGIA.

WATER-MOTOR.

SPECIFICATION forming part of Letters Patent No. 721,661, dated March 3, 1903

Application filed August 21, 1900. Serial No. 27,606. (No model.)

To all whom it may concern:

Be it known that I, BYRON B. BOWER, a citizen of the United States, residing at Bainbridge, in the county of Decatur and State of Georgia, have invented certain new and useful Improvements in Water-Motors, of which the following is a specification.

My invention relates to double-acting reciprocating water-motors wherein an endwise-movable cylindrical valve, which constitutes the cylinder for the piston, is arranged to be reciprocated in a casing having a central and two end chambers.

The object of the invention is to eliminate all back strain or retardation of the main shaft by reason of internal pressure of water upon surfaces of the cylindrical valve and to cause such pressure to be entirely expended in holding the valve in the position it should occupy and also to so construct and organize the parts as to render exact fitting of the cylindrical surfaces unnecessary, all as herein-after set forth in detail.

In the accompanying drawings, Figure 1 shows a side elevation of a water-engine with my improvements applied. Fig. 2 is a view, on an enlarged scale and in longitudinal section, of the casing and the parts contained therein. Fig. 3 is a view in transverse section on the line 3 3 of Fig. 2, but on a reduced scale.

The casing A is made in two sections formed with flanges a, which are bolted together, as indicated. Within the casing there are three chambers—a middle or central chamber A' and end chambers A² A³. Between the chambers A² and A³, respectively, and the central chamber A' are annular flanges a', which act as guides for the cylindrical valve B. The exact proportions in size of the chambers A', A², and A³ is not vital; but preferably the area of each of the chambers A² and A³ is somewhat less than one-third of the area of the chamber A'. Each chamber A² and A³ is provided with an annular series of exit-ports a³ a⁴ just inside the flanges a', and the entrance-port for the water is in the coupling E, located about midway between the ends of the chamber A'.

50 The cylinder B acts both to guide the piston-head C and also as a valve to regulate the entrance and discharge of the fluid. This

cylinder extends through the central chamber A' and into the chambers A² A³. At its opposite ends it is formed with annular flanges b, which are always arranged within the chambers A² A³, and at a short distance therefrom are formed annular flanges b', which are also arranged at all times within the chambers A² A³.

Annular flanges a⁵ are formed on the interior of the casing just inside the flanges b. These flanges a⁵ limit the inward movement of the flanges b. The inward movement of the valve is also limited when the flanges b' 65 abut against the flanges a'. The flanges b fit water-tight in the chambers A² A³, and the cylinder B fits water-tight the flanges a', while being free to reciprocate therein. The cylinder B is also formed with flanges b¹⁰ near 70 opposite ends for limiting its movement.

Ports B² B³ are formed in the sides of the cylinder B some distance from each end thereof. Preferably I employ an annular series of openings or ports in order to obtain a large 75 area for the entrance and discharge of water. These ports B² B³ are so arranged that at times they are located within the chamber A' and at times within the chambers A² A³ in the manner hereinafter described.

The piston C is arranged to reciprocate within the cylinder B, and the rod c extends through packings c' and is connected with a block I', which is adapted to reciprocate vertically in guide-frames O, mounted on the top 85 of the casing. The sliding block I' is pivotally connected at i with a pitman I, which is jointed at its upper end to an arm J, secured to a shaft K, to which is secured a band-wheel (indicated by the dotted lines N) for 90 communicating power to the mechanism to be driven.

Secured to the shaft K is a cam L, preferably of the shape shown and which is adapted to bear upon rollers l, carried by a frame M, 95 which is provided with a slotted opening m, through which the shaft K extends. This frame is connected by a pitman H to a link G, that is jointed to the end of a spring-lever F, pivoted at f to the guide-frame O and jointed at d to a rod D, extending through a packing in the casing A and secured to the cylindrical valve B. The arrangement is such that as the shaft K is rotated by the reciprocation of

the piston the lever F is operated to move the cylindrical valve back and forth at proper times to shift the valve B in such manner as to alternately change the flow of water from 5 one side of the piston to the other.

When water is admitted through the coupling E, it passes into the chamber A', surrounding the cylindrical valve, and when the parts are in the position shown in Fig. 2 the 10 water passes from the chamber A' through the ports B² in the upper part of the valve B down against the piston-head C, which will be driven in the direction indicated by the arrow. The water below the piston will pass 15 out through the ports B³ and through the ports a³ to the outside. As soon as the piston has reached the limit of its downward movement the cam M acts upon the parts connected therewith to raise the rod D, and thus raise 20 the cylindrical valve B, so that the ports B² will be changed from the chamber A' to the chamber A³ and the ports B³ from the chamber A² will be changed to the chamber A', at which time the water will enter through the 25 ports B³ and act upon the under side of the piston-head, causing it to move inwardly, and the water above the piston will pass through the ports B² and directly through the ports a⁴ to the outside. The cylindrical valve is 30 shifted alternately in this way, and water is thus alternately admitted to opposite sides of the piston-rod at proper times to cause its reciprocation.

It will be observed that the cylindrical 35 valve B is of large size and the ports are of large area, permitting large volumes of water to be admitted and discharged at each operation, thus obtaining great power and uniformity in action. The engine may also be 40 operated at high speed.

The cylindrical valve and cylinder are entirely open or unobstructed at both ends, and the annular flanges fit the chambers A² A³. Since the flanges b bear against flanges a⁵ 45 and flanges b' against flanges a', when the cylinder is in either of its positions they form a packing or closure to prevent passage of water between them, and if their faces be properly turned or ground to seat accurately a 50 particularly close fit of the cylinder in its

bearings is not required, and it will at all times work easily notwithstanding the tendency of its surfaces to corrode or receive deposits from the water. Moreover, as may readily be seen from the drawings, all pressure of water on the inlet side of the piston that is exerted upon the cylinder endwise is expended upon the flange b and serves, therefore, to hold the cylinder in the position it should occupy. There is no such pressure 60 tending to move the cylinder in the opposite direction, (in either of its positions,) and therefore there is also no tendency for a retarding strain or load to be thrown upon the main shaft of the engine. So far as I know this 65 behavior of an engine of this general type and the construction by which it is attained are new.

I claim as my invention—

1. In a double-acting reciprocating water-motor, a casing divided into a central and end chambers by interior annular flanges outside of each of which there is another interior annular flange and between the two sets of flanges discharge-ports in the walls of the casing, the water-inlet being formed in the wall of the central chamber, combined with a cylinder open at both ends, fitted to be reciprocated in the casing, having a series of ports in its walls adjacent its ends, and exterior annular flanges coöperating with the flanges on the casing, and a piston reciprocating in the cylinder.

2. In a double-acting reciprocating water-motor, a casing divided by internal annular flanges into three chambers, a water-inlet to the central chamber, exit-ports in the end chambers, a cylinder having ports near each end, fitted to be reciprocated in the casing, acting as a valve, and at each end entirely open 85 and formed with an exterior annular flange fitting the end chamber, and a piston reciprocating in the cylinder.

In testimony whereof I have hereunto subscribed my name.

BYRON B. BOWER.
